A series of photos depicting various smoking pipes, 30 pages.

* cited by examiner

Primary Examiner — Susan Bennett Hattan*Assistant Examiner* — Janice Hallmark(74) Attorney, Agent, or Firm — Michael R. Schacht; Schacht Law Office, Inc.(57) CLAIM

The ornamental design for a smoking pipe, as shown and described.

DESCRIPTION

FIG. 1 is a first end elevation view of a smoking pipe showing my new design;

FIG. 2 is a first side elevation view thereof;

FIG. 3 is second end elevation view thereof;

FIG. 4 is a second side elevation view thereof;

FIG. 5 is a top plan view thereof; and,

FIG. 6 is a bottom plan view thereof.

The broken lines in FIG. 3 depict unclaimed parts of the smoking pipe that form no part of the claimed design.
